AUXILIARY HEADLIGHT SYSTEM

Bruno Tabacchi, Cadiz, Ohio

Application January 18, 1947, Serial No. 722,909

4 Claims. (Cl. 315—83)

1

The invention relates generally to electrical lighting systems for automobiles and more particularly to an improved system for automatically energizing auxiliary headlights when one or both of the regular headlights go out or become defective.

In automobile driving, it often happens that one headlight will be extinguished for some time before the driver is aware of the fact which creates a dangerous hazard because drivers of approaching vehicles cannot accurately gauge the amount of clearance to be given to the defective lighted vehicle.

Moreover, if the headlights go out because a fuse in the automotive lighting system is suddenly blown or because of a short circuit, the driver is left in an exceedingly dangerous situation until the fuse is replaced or the short is remedied.

It is an object of the present invention to provide a novel electrical lighting system for automobiles in which a pair of auxiliary lights is automatically energized when one or both of the regular headlights fail.

Another object is to provide a novel electrical lighting in which either the auxiliary or the regular headlights may be used selectively, and the unused pair is adapted to light automatically upon failure of one or both of the lights of the used pair.

Another object is to provide an improved electrical lighting system including separate circuits having the regular headlights and auxiliary headlights, with means for selectively energizing either or both circuits, and automatic means for lighting one set of lights if one or both lights of the other set fails.

A further object is to provide an improved electrical lighting system having separate circuits with separate fuses to regular and auxiliary headlights.

A still further object is to provide an improved electrical lighting system having auxiliary lights for automatically lighting when the regular headlights fail, said system being easily adaptable for use in standard automotive lighting systems without substantial changes.

These and other objects are accomplished by the parts, elements, constructions, arrangements, and combinations which comprise the present invention, the nature of which is set forth in the following general statement, a preferred embodiment of which is set forth in the following description and illustrated in the accompanying drawing, and which is particularly and distinctly

2

pointed out and set forth in the appended claims forming part hereof.

In general terms, the automotive electrical system comprising the present invention includes a source of electric current, separate circuits including a pair of headlights and a pair of auxiliary lights, a double pole selector switch in each circuit having one side connected to the other circuit, and a relay for connecting said current source normally to one side of each selector switch and adapted upon interruption or current variation of a closed light circuit automatically to connect said current source to the other side of each selector switch.

Referring to the drawing forming part hereof, in which the invention is illustrated, the figure is a wiring diagram of a preferred embodiment of the improved auxiliary headlight system.

Similar numerals refer to similar parts throughout the drawing.

In the drawing a usual automobile storage battery is indicated at 10, having one terminal electrically connected to the usual ground 11, and the other terminal is connected by a conductor 12 through a fuse 13 to a terminal 14 of a main switch 15. The conductor 12 is also connected in front of the fuse 13 by a conductor 16 to another terminal 17 of the main switch 15.

The main switch 15 is a well-known pull switch of the two-position type, and has a contact member 18 which in the position shown supplies current from the terminal 14 to the conductor 19 in the ordinary parking light circuit, and also to the conductor 20 in the tail light and instrument light circuit. When the contact member 18 is pulled upwardly to its other position, current is supplied from the terminal 14 to the conductor 20 so that the tail light circuit stays closed but not to the conductor 19, and the terminal 17 is connected by the contact member 18 to the terminal 21 for supplying current to the headlight circuit.

A conductor 22 connects the terminal 21 to the coil of an electromagnetic relay 23 having an armature 24 movable therein, and a conductor 25 connects the other end of a coil to one side of each of two double pole selector switches 26 and 27 respectively. A tension spring 28 is connected at one end to the armature 24 of the relay 23 for urging it away from the relay to a position where the cross bar of the armature will make connection between a conductor 29 which leads from the terminal 21 of the main switch and a conductor 30 which is connected to the other

sides of each of the double pole selector switches 26 and 27. The tension spring 28 is adjustably connected at its other end to a block 31, so that the tension of the spring may be adjusted relative to the magnetic pull exerted on the armature by the relay 23.

The terminals 33 and 33a on the side of switch 26 to which conductor 25 is connected preferably make connection when the switch is closed with a conductor 34 which is connected through a fuse 35 and a single pole switch 36 to either the high beam filaments 37 or the low beam filaments 38 of the regular headlights. The single pole switch 36 is manually operated, preferably by the usual foot button on the floor board of the automobile, so as to selectively connect either the high beam or the low beam filaments of the regular headlights in the circuit, the headlights being grounded in the usual fashion.

The terminals 39 and 39a on the side of switch 27 to which the conductor 25 is connected preferably make connection when the switch is closed with a conductor 40 which is connected through a fuse 41 and conductors 42 with a pair of auxiliary headlights 43 in parallel. The headlights 43 may be fog lights if desired or other road lights, and are grounded to the automobile body in a usual fashion.

The other side of the switch 26 to which the conductor 30 is connected has terminals 44 and 44a which are connected by a conductor 45 to the conductor 40 at a point between switch 27 and fuse 41. Similarly the other side of switch 27 has terminals 46 and 46a which are connected by a conductor 47 to the conductor 34 at a point between switch 26 and fuse 35.

Accordingly, when the switch 26 is closed the terminals 33 and 33a are connected with the conductor 34 of the regular headlight circuit, and the terminals 44 and 44a are connected by the conductor 45 with the auxiliary headlight circuit in front of fuse 41. Similarly, if the switch 27 is closed the terminals 39 and 39a are connected by conductor 40 with the auxiliary headlight circuit, and at the same time the terminal 46 is connected by the conductor 47 with the regular headlight circuit in front of fuse 35.

In the operation of the improved auxiliary headlight system, assuming switch 27 is open and that switch 26 is closed to connect terminals 33 and 33a on the first side of the switch 26, if the contact element 18 of the main switch 15 is moved upwardly to close the headlight circuit by connecting terminals 17 and 21, the current flowing through the coil of the relay 23 will exert an electromagnetic pull on the armature 24 to disconnect conductors 29 and 30, and current will flow through the coil to conductor 25. In such case, current will flow from the conductor 25 through the terminals 33 and 33a of the switch, conductor 34, fuse 35, switch 36 and through the filaments 37 of the regular headlights, thus energizing the same. In this case no current flows through terminals 44 and 44a to energize the auxiliary headlights 43 because conductors 29 and 30 are disconnected. If both of the regular headlights go out because of the filaments burning out or because of a short circuit, the electromagnetic pull exerted by the relay 23 will cease, and the spring 28 will pull the armature 24 to a position connecting the conductors 29 and 30. In such case, the current will flow from conductor 30 through terminals 44 and 44a on the second side of switch 26 and conductor 45 into the auxiliary headlight circuit where it flows through

conductor 40, fuse 41 and conductors 42 to energize the auxiliary headlights 43.

With the system in this condition, as soon as the regular headlights are replaced or the short circuit is repaired, the current flowing through the relay 23 will pull the armature 24 within the coil and break the circuit between conductors 29 and 30 so as to extinguish the auxiliary lights and again energize the regular headlights. If desired, the tension of spring 28 may be adjusted so as to allow the spring to move the armature into contact with conductors 29 and 30 when the amperage of the light circuit is reduced by only one regular headlight burning or shorting out. In other words, if the current flowing through the circuit with both headlights on is approximately 15 amperes, the spring 28 can be adjusted so that if one headlight burns out and reduces the amperage to about 8 amperes, the spring will have sufficient tension to overcome the weakened pull of the relay and make the connection between conductors 29 and 30.

If desired, a warning light 48 may be connected in parallel with the conductor 30 to indicate to the driver of the automobile when the regular headlight circuit is off and the auxiliary light circuit is closed. Such warning light may be conveniently located on the instrument panel.

If it is desired to use the auxiliary lights 43 and not the regular headlights, as in a case where the auxiliary lights are fog lights, the same may be accomplished by opening the switch 26 and closing the switch 27, in which case the current will flow from the relay through conductor 25 and terminals 39 and 39a on the first side of switch 27 to the auxiliary light circuit. Under these circumstances, if the auxiliary light circuit is interrupted or varied as by one or both of the auxiliary lights going out, the armature 24 will automatically make contact between conductors 29 and 30 and current will flow from conductor 30 through terminals 46 and 46a on the second side of switch 27 and conductor 47 to the regular headlight circuit, thus immediately energizing the regular headlights. Likewise, if it is desired to utilize both the regular headlights and the auxiliary lights at the same time, both switches 26 and 27 are closed, and if anything happens to extinguish one or both lights of either pair, the other pair will stay lighted.

Both the headlight circuit and the auxiliary light circuit are protected from overloads due, for example, to defective wiring and short circuits, by the fuses 35 and 41 respectively and if for any reason one fuse is blown the other circuit will continue to energize its pair of headlights until the damage to the first circuit is remedied and the fuse replaced.

Accordingly, the improved auxiliary headlight system provides for instantaneously and automatically lighting a set of auxiliary headlights when one or both of the regular headlights fail, thus providing for greatly increased safety to the driver of the automobile as well as to drivers of approaching vehicles, because they are not required to guess at the exact location of the automobile on the roadway as is the case when the automobile is driven with one headlight or with no headlights lighted.

The improved system provides for increased flexibility in the use of one or both pair of headlights always with the safety feature of automatically lighting the second set when one or both of the lights of the set being used fails. The improved auxiliary headlight system is simple

and inexpensive and is easily adapted for use with standard automobile lighting systems without requiring substantial changes.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction.

Having now described the invention, the construction, the operation and use, and a preferred embodiment thereof, and the advantageous new and useful results obtained thereby; the new and useful constructions, and reasonable mechanical equivalents thereof obvious to those skilled in the art, are set forth in the appended claims.

I claim:

1. An electrical lighting system for automobiles including a source of electric current and a main switch connected thereto, a headlight circuit and a separate auxiliary light circuit, a first double pole selector switch having its first side connected to the headlight circuit and its second side connected to the auxiliary circuit, a second double pole selector switch having its first side connected to the auxiliary circuit and its second side connected to the headlight circuit, and an electromagnetic relay for connecting said main switch normally to said first side of each of said first and second selector switches, and adapted upon current variation through a closed light circuit automatically to connect said main switch with the second side of each selector switch.

2. An electrical lighting system for automobiles including a source of electric current and a main switch connected thereto, a headlight circuit and a separate auxiliary light circuit, a first double pole selector switch having its first side connected to the headlight circuit and its second side connected to the auxiliary circuit, a second double pole selector switch having its first side connected to the auxiliary circuit and its second side connected to the headlight circuit, an electromagnetic relay having a coil connecting said main switch to said first side of each selector switch, and a spring for moving the armature of said relay to a position connecting said main switch with said second side of each selector switch when current through the relay coil is substantially reduced.

3. An electrical lighting system for automobiles including a source of electric current and a main switch connected thereto, a headlight circuit and a separate auxiliary light circuit, a first double pole selector switch having its first side connected to said headlight circuit and its second side connected to said auxiliary circuit, a second double pole selector switch having its first side connected to said auxiliary circuit and its second side connected to said headlight circuit, a fuse in said headlight circuit beyond the connection thereto of said second selector switch, a fuse in said auxiliary circuit beyond the connection thereto of said first selector switch, and an electromagnetic relay for connecting said main switch normally to said first side of each of said selector switches and adapted upon current variation through a closed light circuit automatically to connect said main switch with said second side of each selector switch.
4. An electrical lighting system for automobiles including a source of electric current and a main switch connected thereto, a headlight circuit and a separate auxiliary light circuit, a first double pole selector switch having its first side connected to said headlight circuit and its second side connected to said auxiliary circuit, a second double pole selector switch having its first side connected to said auxiliary circuit and its second side connected to said headlight circuit, a fuse in said headlight circuit beyond the connection thereto of said second selector switch, a fuse in said auxiliary circuit beyond the connection thereto of said first selector switch, an electromagnetic relay having a coil connecting said main switch normally to said first side of each selector switch, and a spring for moving the armature of said relay to a position connecting said main switch with the second side of each selector switch when current through the relay coil is substantially reduced.
